UNITED STATES PATENT OFFICE.

WILLIAM DEDERICH AND SIGMUND WILLNER, OF LONDON, ENGLAND.

BURNER FOR FLUID FUEL.

1,417,146.

Specification of Letters Patent. Patented May 23, 1922.

Application filed April 22, 1920. Serial No. 375,875.

To all whom it may concern:

Be it known that we, WILLIAM DEDERICH, a subject of the King of England, and SIGMUND WILLNER, formerly a subject of the German Empire, but now denationalized, both residing in London, England, have invented certain new and useful Improvements in Burners for Fluid Fuel; of which the following is a specification.

10 This invention is for improvements in or relating to burners for fluid-fuel, and has particular reference to those burners in which the combustion of fuel, such as heavy hydrocarbons of the nature of tar or pitch, 15 or other viscous fluid fuel is effected.

Hitherto in burners in which such fuel is employed, cold or warmed fuel has been introduced into the burner with or without pressure, either through spray nozzles or 20 by means of steam injectors, and in such burners the fuel has been in the main discharged in the form of a spray or liquid, only a small portion of it being discharged in the form of vapour, whereas a burner according to the present invention discharges 25 the fuel in the form of vapour with a comparatively small proportion, if any, of liquid particles in it. In some of the burners already known the fuel has in the first place 30 been mixed with steam or superheated steam or compressed air, and then this mixture has been carried into the burner in a vaporous form.

In both of these types of burners previously used, however, there has also been the further difficulty that they tend to become clogged by particles of fuel clinging either to the main bore of the burner or to the outlet therefrom; this difficulty is overcome by means of the present invention.

A burner according to this invention is characterized by the provision of a vaporizing-chamber wherein a heated impact surface is provided (for example one wall of the chamber or a member therein), and by means to project a mixed stream of fuel and hot carrying-fluid therefrom to the said surface. The outlet from the said chamber may be, for the purpose described, arranged 45 at a point not directly in line with the direction of said projection of the incoming fuel.

A burner constructed as above specified

may, according to this invention, have the said vaporizing chamber formed with a constricted outlet for the purpose described and be provided with a second impact surface within the burner to receive the issuing stream from the said outlet.

In the accompanying drawings, 60

Figure 1 is a central longitudinal section through a burner, constructed according to one method of carrying out this invention;

Figure 2 is a section of Figure 1 on the line 2—2;

Figure 3 is a longitudinal central section through a burner, constructed according to another method of carrying out this invention;

Figure 4 is a central section through the burner-nozzle in a plane at right-angles to the section in Figure 3;

Figure 5 is an end view of the burner-nozzle, and

Figure 6 is a section through Figure 3 on the line 6—6.

Like letters indicate like parts throughout the drawings.

In the construction shown in Figure 1, the burner-tube A is contracted at the centre 80 and situated about centrally therein is a vaporizing-chamber B. This chamber is formed by a plate B¹ which constitutes the heated member or wall of the vaporizing-chamber, and is disposed within the bore of 85 the burner and opposite the end of the inlet conduit for the fuel indicated at C so as to afford an impact surface on to which the fuel is projected. The plate B¹ extends right across the upper portion of the bore 90 of the burner so that a pocket is formed in the upper wall which is closed at that end remote from the nozzle D but is open at the end which is towards the nozzle as shown at B². Screwed into the top of the burner 95 is a fitting E in which is provided the conduit C already referred to, and two other conduits E¹ and E² respectively. The conduits E¹ and E² have communication with a nipple E³ for connection to a supply-conduit for steam or any other selected heating medium which can be supplied under pressure, and the conduit C has a nipple C¹ for connection to a conduit whereby the viscous fuel may be supplied. The conduits E¹, E² 100 and C constitute, in effect an injector-type

device whereby a stream of mixed fuel and carrying fluid are projected into the chamber B. As shown in Figure 2, the mouth of the conduit C lies between the mouths of the 5 conduits E¹ and E², and these latter conduits themselves extend up on opposite sides of the conduit C.

At the back of the burner-tube A, a steam-nozzle F is mounted, being provided with 10 means outside the burner for attachment to a conduit for the main supply of steam, or such other hot fluid may be employed for driving the fuel forward and completing its vaporization. An air-admission plate F¹ is 15 situated at the back of the burner and can be adjusted to regulate the amount of air allowed to pass into the burner.

Opposite the outlet B² from the vaporizing-chamber B, the upper wall of the burner is sloped downwards as shown at A¹, constituting at this point, a second impact surface 20 for the fuel.

The operation of this burner is as follows:—

Viscous fuel such as tar is fed down the 25 central conduit C on to the plate B¹ which constitutes one wall of the vaporizing-chamber B. The main steam supply fed in by the nozzle F strikes this plate and keeps it hot so that the fuel projected there onto is 30 vaporized. The vaporization is further assisted by the steam admitted by the conduits E¹, E², which strikes the plate in front of and also behind the incoming jet of fuel. 35 This steam, further, drives the fuel off the plate B¹ and out from the vaporizing-chamber by the outlet B² on to the second impact surface A¹, after which it is caught by the main supply of steam and carried to the 40 nozzle D where vaporization is completed prior to its being discharged from the mouth of the nozzle. The steam in the conduits E¹, E² also warms the fuel before it reaches the vaporizing-chamber, and although the conduits C, E¹ and E² are shown somewhat short, it will be appreciated that they can 45 be made of any length desired so as to give time for the fuel to become sufficiently warmed on its way to the vaporizing-chamber to make it flow easily into the same.

In the construction shown in Figures 3 to 6, the burner-tube G takes the form of a straight barrel having screwed into its forward end a nozzle G¹ and into the back end 55 a somewhat egg-shaped vaporizing-chamber H.

The vaporizing-chamber is in line with the bore of the burner, and the conduit for the main supply of steam or other hot fluid 60 extends straight through the vaporizing-chamber and well in to the burner-tube in which it is centrally situated, but which it does not fill laterally.

At the back of the vaporizing-chamber 65 and at the top thereof an injector-type de-

vice is provided comprising a conduit H¹ by which steam or other hot fluid enters the chamber, and situated centrally within which is another conduit H² for the viscous fuel. The outlet of this inner conduit lies directly 70 opposite the conduit J for the main steam supply which extends through the vaporizing-chamber in a direction which is transverse to the direction of travel of the fuel entering by the conduit H². The conduit J 75 thus constitutes a heated impact surface for the fuel projected from the nozzle of the conduit H².

At the point where the vaporizing-chamber communicates with the burner-tube a series of spiral-baffles K, Figures 3 and 6, are provided, and the vaporizing-chamber is larger than the bore of the burner-tube so that it is contracted to meet the same, and the outlet lies at right-angles to the inlet. 80

The end of the conduit J enters the rear end of the nozzle G¹ and the passage through this rear end is contracted as shown at G², this portion constituting a second impact surface for the fuel. Moreover the forward 90 end of the conduit J co-operates with the contraction at G² to operate as an injector device whereby the mixture is projected violently into an enlargement G³. The nozzle then has the enlargement G³ followed by 95 another contraction G⁴ and a further enlargement G⁵. The mouth of the nozzle is flattened so that it is wide in one direction and narrow in the other as shown at G⁶, Figure 5. 100

The operation of this burner is as follows:—

The hydrocarbon fuel is fed down the conduit H² and is warmed by the steam admitted by the conduit H¹. The fuel and 105 steam are projected into the vaporizing-chamber H and impinge against the conduit J, which is heated by the main steam supply passing through it. The fuel and steam also impinge against the bottom wall of the 110 chamber H which is kept hot by its being in metallic contact with the wall of the conduit J. The shape of the vaporizing-chamber H causes the steam and fuel to be well 115 mixed in the chamber, and this is further effected by the spiral-baffles K, which the fuel and steam pass as they leave the vaporizing-chamber and enter the burner-tube. Here vaporization is again assisted by the centrally situated main steam-conduit J, and 120 by the whirling motion in the tube G together with the frictional action against the walls of this part. Vaporization is completed by the fuel with its initial steam-supply coming into contact with the main 125 steam-supply in the nozzle G¹. The contraction G² followed by the enlargement G³ and another contraction G⁴ followed by another enlargement G⁵, is a device whereby the mixture is subjected to a succession of 130

rapid rises and falls of pressure after leaving the impact surface, the object of effecting these changes of pressure being to assist in completing the vaporization of the fuel.

5 It is found that with either of these forms of burner, thorough vaporization of the fuel is effected and clogging does not occur. The steam which is fed in with the fuel helps to prevent clogging as it impinges against such 10 fuel as adheres temporarily to the wall of the vaporizer or the heated member therein, so that the fuel is thus carried forward and made to mix intimately with the steam by the various contracted portions through 15 which it passes, with the result that it is thoroughly vaporized.

As has been indicated throughout this specification other heating-fluids can be used instead of steam, and the invention is not 20 restricted to the use of tar as the fuel.

What we claim as our invention and desire to secure by Letters Patent is:—

1. In a burner for viscous fuels, the combination of a burner body, a vaporizing 25 chamber within the burner body having an outlet converging towards the nozzle of the burner and distinct from the burner tube, an inlet into the said vaporizing chamber, a second inlet into said vaporizing chamber 30 side by side with the first said inlet, an impact surface within the vaporizing chamber and situated directly across the path of fluid entering by the said inlets, means for heating the said impact surface, a second impact surface within the burner situated between the vaporizing chamber and the nozzle in the path of fluid passing from the former to the latter, means for supplying fuel to one of 35 said inlets and hot carrying-fluid therefor to the other of the said inlets, and means for introducing a supply of hot fluid at the said second impact surface into the stream from the vaporizing chamber, substantially as described.

45 2. A burner body whereof the delivery end comprises at least two portions of larger bore than the immediately posterior portion and a constricted bore between each pair of adjacent said portions of larger bore, a vaporizing chamber within the burner body 50 having an outlet converging towards the nozzle of the burner and distinct from the burner tube, an inlet into the said vaporizing chamber, a second inlet into the vaporizing 55 chamber side by side with the first said inlet, an impact surface within the vaporizing chamber and situated directly across the path of fluid entering by the said inlets, means for heating the said impact surface, a second

60 impact surface within the burner situated between the vaporizing chamber and the nozzle in the path of fluid passing from the former to the latter, means for supplying fuel to one of the said inlets and hot carrying- 65 fluid therefor to the other of the said inlets,

and means for introducing a supply of hot fluid at the said second impact surface into the stream issuing from the vaporizing chamber, substantially as described.

3. A burner for viscous fuels, comprising 70 a vaporizing chamber having a wall in the form of a plate which spans a segment of the bore of the burner forming a pocket on one side wall thereof, said pocket being closed by the plate at that end which is away 75 from the nozzle of the burner and open at the other end, means feeding the fuel into said pocket on said plate, and means for continuously heating said plate, substantially as described.

4. A burner for viscous fuels, comprising the combination with a burner-tube, a vaporizing-chamber that opens into the tube and has an impact surface, and fuel supply means 85 for projecting a stream of heated fuel on to 80 said impact surface, of a conduit for heating said impact surface, and injecting into said stream after its contact with said impact surface, a stream of hot fluid, said conduit being so arranged relatively to said fuel-supply means that part of the incoming fuel impacts on said conduit and all the fuel is heated by the said hot fluid as both flow towards the outlet of the burner tube.

5. A burner for viscous fuels, comprising 90 the combination of a burner-tube, a vaporizing-chamber that is situated in line with the bore of the tube, opens into the latter, and has a portion of its wall constituting an impact surface, a conduit that traverses the 95 vaporizing-chamber and extends through its outlet for supplying a hot fluid through the tube, a portion of the wall of said conduit in the vaporizing-chamber constituting a second impact surface, and fuel-supply 100 means for projecting a stream of heated fuel on to both of said impact surfaces.

6. A burner for viscous fuels, comprising 105 the combination of a burner-tube, a vaporizing-chamber that is situated in line with the bore of the tube, and has a constricted outlet opening into the tube, a conduit that traverses the vaporizing-chamber and extends through its outlet for supplying a 110 hot fluid through the tube, a portion of the wall of said conduit in the vaporizing-chamber constituting an impact surface, and fuel-supply means for projecting a stream of heated fuel on to said impact surface.

7. A burner for viscous fuels comprising 115 in combination a burner-tube, a vaporizing-chamber situated in line with the bore of the burner-tube and having its outlet opening into the same, a fluid-supply conduit for 120 hot fluid that extends through the vaporizing-chamber and its outlet and along the bore of the burner-tube, the external diameter of which conduit is less than the internal diameter of the burner-tube, whereby 125 the 130

space between the said conduit and the internal wall of the burner-tube constitutes a combined mixing and vaporizing-chamber, and means for projecting a stream of heated fuel on to the conduit in the former vaporizing-chamber and on to the wall of the latter, substantially as described.

In testimony whereof we have signed our

names to this specification in the presence of two subscribing witnesses.
